CLAIM

The ornamental design for an exercise mask, as shown and described.

DESCRIPTION

FIG. 1 is a bottom plan view of an exercise mask showing my new design;

FIG. 2 is a top plan view thereof;

FIG. 3 is a left side elevational view thereof;

FIG. 4 is a right side elevational view thereof;

FIG. 5 is a front elevation view thereof;

FIG. 6 is a rear elevation view thereof;

FIG. 7 is a front perspective view thereof; and,

FIG. 8 is a rear perspective view thereof.

The broken lines in the drawings depict portions of the exercise mask that form no part of the claimed design.
